UNITED STATES PATENT OFFICE.

ALFRED H. NYLEN, OF PIEDMONT, CALIFORNIA.

SALVAGING APPARATUS.

1,272,302.

Specification of Letters Patent. Patented July 9, 1918.

Application filed January 31, 1917. Serial No. 145,749.

To all whom it may concern:

Be it known that I, ALFRED H. NYLEN, citizen of the United States, residing at Piedmont, in the county of Alameda and 5 State of California, have invented certain new and useful Improvements in Salvaging Apparatus, of which the following is a specification.

This invention relates to apparatus for 10 raising sunken vessels, the object thereof being to provide an apparatus by means of which a sunken vessel can be located and raised without the use of divers, grappling hooks, or any similar means.

15 This I accomplish by means of a marker buoy which will float to the surface of the water as soon as the vessel is sunk, and to which is attached light lines which will release at the will of the wrecker numerous 20 other buoys located at intervals on the vessel, and enable him thereby to attach heavy lifting hawsers to said vessel as more fully explained and described in the following specification, in which:

25 Figure 1 is a view of a sunken steamer with its marker buoy showing its location.

Fig. 2 is a similar view, having a number of its line buoys released.

Fig. 3 is a similar view showing a vessel 30 being raised.

Fig. 4 is a cross section of a vessel showing a unit of my method as installed.

Fig. 5 is a fragmentary section near the 35 bow of a vessel, showing the location of the marker buoys and one of the line buoys.

Fig. 6 is an enlarged view of a marker buoy.

Fig. 7 is an enlarged fragmentary view of 40 a line buoy and the means for holding same down until released.

Fig. 8 is a longitudinal section of a vessel showing an alternative manner of installation of my improved system.

Fig. 9 is a view showing a method of raising 45 a vessel when this alternate system is in use.

Preferably near the bow of a vessel 1 and in an entirely unobstructed spot, is located a cylindrical chamber 2, sunk flush with the 50 top deck 3, and adapted to receive a buoy 4 and a considerable length of light rope 5 besides a plurality of lines 6, each one of which is suitably run to the end of a slideable bolt 7 in a receptacle 8 in which is 55 seated a buoy 9. To the under end of each

buoy 9 is secured the end of an endless light line 10, the same passing out of the receptacle over the deck of the ship and through tube or U-shaped pipe 11, which extends around the hull of the ship alongside 60 a rib 12 thereof, to which rib the tube is attached. These tubular units are suitably distributed throughout the vessel, each one, of course, having its line buoy and endless line as described.

65 It is, of course, understood that all these buoys must be so located on the topmost possible point, and away from any obstruction which might prevent their reaching the surface of the water when released.

70 Loose buoyant hatches 13 are placed over all buoy-nests so as to prevent dirt, etc., from lodging therein while the vessel is in service, and adapted to float off and uncover the receptacles 5 and 8 when the ship 75 sinks.

The buoy 4 is preferably provided with a watertight compartment 14 therein in which may be placed a document 15 giving the name, tonnage, etc., of the vessel, location 80 of the buoys thereon, as well as any additional information which may be of service to the wreckers.

85 Each of the lines 6 is of a different color or otherwise marked to identify same, so that by reference to the above mentioned document the wreckers may release any particular buoy they desire by pulling the line corresponding to the designation given by said document. In the modification shown 90 in Fig. 8, the tubes 11 extend through the center of the ship.

The operation is as follows:

Presuming a searching boat to have located the marker buoy of a sunken vessel, 95 the receptacle on said buoy is opened and the document therein taken out and perused.

The line buoys may then be released at will by hauling on each of light lines 6 in turn, thus pulling out bolt 7 from each of 100 the buoys 8 and releasing same, causing them to float to the surface, as shown in Fig. 2. The light lines 10 are then cut, and heavy hawsers attached to one end thereof, the other end being pulled up, pulling the hawsers down and through the tubular members 11, and the ends thereof are then attached to the lifting mechanism of lighters 105 16 as shown in Fig. 3. This is done with all of the line buoy units, until sufficient lifting 110

power is had to raise the vessel. If so desired, in order to aid this, empty casks are attached to the heavy hawsers at intervals as shown by Fig. 9, thus aiding the lifting by their buoyant effect. In the method as shown in Figs. 3 and 4, the vessel is raised from the sides, while in that as shown by Figs. 9 and 10, the pull is on the center line of the vessel.

10 Having described my invention I claim as new and desire to secure by Letters Patent:

1. In an apparatus for raising sunken vessels, a marker buoy mounted on the vessel so as to float to the surface of the water upon sinking of the vessel, a line connecting said buoy to the vessel, a line float mounted on the vessel, means carried by said marker buoy for releasing said float to allow the float to float to the surface of the water, and 20 means carried by said float for attaching a hawser to the vessel to raise the vessel.

2. In an apparatus for raising sunken vessels, a marker buoy mounted on the vessel so as to float to the surface of the water upon sinking of the vessel, a line connecting said buoy to the vessel, a line float mounted on the vessel, means carried by said marker buoy for releasing said float to allow the float to float to the surface of the water, a U-shaped tube mounted on the vessel with its side members extending upwardly, and a light line extending through said tube and connected to said float.

3. In an apparatus for raising sunken vessels, a marker buoy mounted on the vessel so as to float to the surface of the water upon sinking of the vessel, a line connecting said buoy to the vessel, a line float mounted on the vessel, means carried by said marker buoy for releasing said float to allow the float to float to the surface of the water, and a U-shaped tube extending around the hull of the ship with its connecting member resting against the bottom of the ship and its side members extending upwardly alongside the sides of the ship, and a light line extend-

ing through said tube and connected to said float.

4. In an apparatus for raising sunken vessels, a receptacle mounted on the vessel, a marker buoy freely mounted in said receptacle so as to float to the surface of the water when the vessel sinks, a line connecting said buoy to the vessel, floats mounted on the vessel and normally locked to the vessel, means connected to said marker buoy for releasing said floats, and means associated with said floats for attaching a hawser to the sunken vessel to raise the same. 50 55

5. In an apparatus for raising sunken vessels, a marker buoy mounted on the vessel to float on the surface of the water when the vessel is sunk, a line connecting said buoy to the vessel, receptacles mounted on the vessels, floats mounted in said receptacles and 60 normally locked therein, means connected to said marker buoy for releasing said floats so that they may float to the surface of the water, and means associated with said floats for attaching a hawser to the sunken vessel. 65 70

6. In an apparatus for raising sunken vessels, a receptacle mounted on the vessel, a buoy resting in said receptacle, a rope connected to said buoy and the vessel normally packed within said receptacle, said buoy being adapted to float to the surface of the water when the vessel is sunk and said line being adapted to unpack to permit said buoy to leave the receptacle and float to the surface of the water, a second receptacle mounted on the vessel, means for normally locking said float in the receptacle, a rope connected at its respective ends to said float and to the vessel and normally packed in said receptacle, a line connected to the rope of said buoy and to said locking means for releasing said float so that said float may float to the surface of the water with its connecting rope, and means associated with the float rope for attaching a hawser to the sunken ship. 75 80 85 90

In testimony whereof I affix my signature.

ALFRED H. NYLEN.
